UNITED STATES PATENT OFFICE.

LEE B. SKINNER, OF DUNEDIN, FLORIDA, ASSIGNOR TO SKINNER MACHINERY COMPANY, OF DUNEDIN, FLORIDA, A CORPORATION OF FLORIDA.

ORCHARD HEATER.

Application filed April 16, 1923. Serial No. 632,386.

To all whom it may concern:

Be it known that I, LEE B. SKINNER, a citizen of the United States, residing at Dunedin, in the county of Pinellas and State 5 of Florida, have invented certain new and useful Improvements in Orchard Heaters, of which the following is a specification.

The present invention relates to orchard heaters and more particularly to that type 10 of heater for burning solid fuel, such as charcoal, coke and like products.

The present invention has for its principal objects to provide a grate with a receptacle 15 therein located at a point beneath the fuel igniting opening.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be 20 25 sorted to without departing from the spirit or sacrificing any of the advantages of the invention.

To more clearly comprehend the invention, reference is directed to the accompanying 30 drawings, wherein—

Fig. 1 is a vertical sectional view of the preferred embodiment of my invention, illustrating an igniting torch inserted into the igniting opening.

Fig. 2 is a view in perspective of the 35 grate removed from the heater.

Referring more particularly to the drawings, wherein like characters of reference 40 designate corresponding parts—1 indicates the metallic casing of the heater having an open top 2 and formed in its side walls adjacent its bottom with draft openings 3 and with an igniting or torch receiving opening 4. Within the base of the casing is positioned a fire grate 5, preferably formed with 45 the spaced grate bars 6 and having cast integral therewith at one side of the grate a receptacle or depression 7. When the grate is positioned within the casing, the receptacle or depression 7 is disposed at a point

below the opening 4, as illustrated in Fig. 1. Suitable supporting legs 8 are utilized for raising the casing off of the ground and permitting a draft to pass upwardly between the grate bars 6 into the casing.

In igniting the body 9 of coke, charcoal or like solid fuel, the operator employs a lighting torch 10 formed with a tubular extension 11 carrying at its end a wick 12. The torch is filled with suitable fuel such as coal oil and the wick is lighted. The extension 11 is then projected at a downward inclination through the opening 4 and while the fuel in the lighting torch discharges in a flaming condition around the wick 12 and collects within the receptacle 7, being retained therein while burning until it is completely consumed.

This manner of igniting the fuel in the heater requires only sufficient of the operator's time to deposit a body of ignited fuel in the receptacle 7, and enables the igniting of a great number of heaters within a short period of time. The flaming liquid fuel within the receptacle 7 rapidly ignites the 70 75 solid fuel and within a short time after being ignited the heater is in full operation.

While I have illustrated the receptacle at one side of the grate, it will be readily understood that the same may be located at any 80 other convenient point.

I claim:—

1. An orchard heater comprising a casing, provided in its side wall with a draft opening and a fire igniting orifice, and a fire supporting grate within the casing, and provided adjacent its peripheral edge with a liquid fuel receiving receptacle wholly within the casing.

2. An orchard heater comprising a casing, provided in its wall with a draft opening and a fire igniting orifice, a fire supporting grate within the casing, and a liquid fuel receiving receptacle within said grate and wholly within the casing at a point below 95 said fire igniting orifice.

In testimony whereof I have signed my name to this specification.

LEE B. SKINNER.
